UNITED STATES PATENT OFFICE.

ANTONIO CASALE, OF SCRANTON, PENNSYLVANIA.

TRAIN-CONTROL SYSTEM.

1,148,442.

Specification of Letters Patent. Patented July 27, 1915.

Application filed September 23, 1914. Serial No. 863,112.

To all whom it may concern:

Be it known that I, ANTONIO CASALE, a citizen of the United States, residing at Scranton, in the county of Lackawanna and State of Pennsylvania, have invented a new and useful Train-Control System, of which the following is a specification.

The present invention relates to improvements in train control systems.

10 One object of the invention is the provision of a novel and improved electrical system, embodying a normally closed train carried circuit, so that the failure of any material portion of the system will produce 15 a danger or emergency condition, and cause the controlling apparatus of the train to be operated to check the movement of the train.

A further object of the present invention, 20 is the provision of a system of this character, which will produce the slowing down or retardation of the speed of a train approaching another train within a predetermined zone, and to finally stop such train when it has proceeded farther into such zone, thus 25 producing an emergency stop at a safe distance between the trains.

A further object of the invention, is the 30 provision of a train control system having novel means for shutting off the steam or operating power to slow the speed of the train, under caution conditions, and to 35 finally completely shut off the steam or power and apply the air brakes to bring the train to a halt under emergency or danger conditions.

With the foregoing and other objects in view which will appear as the description proceeds, the invention resides in the combination and arrangement of parts and in 40 the details of construction hereinafter described and claimed, it being understood that changes in the precise embodiment of the invention herein disclosed can be made within the scope of what is claimed without 45 departing from the spirit of the invention.

In the drawings—Figure 1 is a diagrammatic view of a portion of the track, three blocks being shown, and one block only occupied by a train with apparatus in combination therewith. Fig. 2 is a detail view 50 of the circuit controlling shoe member carried by the locomotive or train, the same being in normal position. Fig. 3 is a view showing the same operated in connection 55 with the ramp. Fig. 4 is a similar view to

Fig. 2 of a modified form of shoe actuated switch. Fig. 5 is a similar view to Fig. 3 of such modified form. Fig. 6 is an enlarged detail view of still another modified form of shoe actuated switch, the parts being in the position they assume when actuated by the ramp. Fig. 7 is an enlarged detail view of one method of actuating the venting valve of the air brake system showing means whereby the engineman may control the same to prevent its automatic operation and also to permit the train under the control of the engineman to enter a prohibited zone. Fig. 8 is a diagrammatic view showing the present track installation used in connection with a block signal system.

Referring to the drawings, and more particularly to Figs. 1 and 2 thereof, the numerals 1 and 2 designate the rail sections of the respective blocks A, B, and C, the same being insulated from each other, so that the respective rail blocks are only electrically continuous.

As illustrated in Fig. 1 disposed adjacent the end of the block A are the two short rail sections 3—3' while disposed adjacent the opposite end of the block B are the two short rail sections 6 and 11, the purpose of which will presently appear.

Connected to one end of the rail section 3 is a conductor 4, which has interposed therein, a resistance 5, the opposite end of the conductor being connected to the adjacent end of the rail 6, while the conductor 7 connects the opposite end of the rail 6 to the inner end of the rail section 1 at the entrance of the block C. The conductor 8 is bridged across the opposite ends of the rails 1 and 2 in block C and has interposed therebetween a resistance 9, while connected to the opposite end of the rail 2 is a conductor 10, which leads to and is connected to one end of the short rail section 11 at the outlet end of the block C, a conductor 12 connecting the rail 11 to the short rail section 3'.

Carried by the train T are the two shoe controlled switches S, the detail construction of which is set forth in the various figures from 2 to 6.

Each one of the respective shoe controlled switch mechanisms is provided with the two switch members 13 and 14, the switch member 14 of which has led therefrom, a conductor 15 which in turn is connected to the conductor 16 of the cab apparatus as illus-

trated in Fig. 1. Thus as the switches 14 and 15 are normally closed, the following circuit will be maintained upon the cab so that the solenoid 19 will be energized and 5 the valve 39 will be held in closed position. This circuit includes the battery 17, the conductor 18, the solenoid 19, the conductor 20, the movable switch member 13, the stationary switch member 14, and the conductors 10 15 and 16. Thus when the respective shoe members S are out of contact with the rail sections 3—3' or 6—11, the above mentioned circuit is energized, and the solenoid 19 is energized, thus maintaining upon the train 15 a closed circuit to hold the valve 39 in closed position.

As the shoes S engage the rail sections 3—3', the switch members 13 and 14 are opened, as will presently appear, but immediately 20 the following circuit is closed so as to maintain the energization of the solenoid 19. This circuit includes the battery 21, the conductor 22, the shoe S which engages the short rail 3', the short rail 3', the conductor 25 25 12, the short rail 11, the conductor 10, the rail 2 of the block C, the conductor 8 and its resistance 9, the traffic rail 1 of the block C, the conductor 7, the short rail 6, the resistance 5 and the conductor 4, the short 30 rail 3, the remaining shoe S, the conductor 23, the coil 24, which is inoperative when the resistances 5 and 9 are thrown into the line, the conductor 25, the coil 26 which is also inoperative when the resistances 5 and 35 9 are thrown into the line, but which is operative when the resistance 5 only is placed in the line, as will presently appear, the conductor 27, the coil 28 which is operative when both resistance 5 and 9 are connected 40 in the line, and the conductor 29. Thus when this circuit is closed, and the electromagnet 28 energized, the armature 30 is attracted thereby, against the action of the spring 31, closing the switch 32—33. Thus 45 the circuit to the solenoid 19 which has been previously opened due to the switches 13 and 14 is closed, and includes the battery 17, the conductor 18, the solenoid 19, the conductors 20 and 34, the switch 32—33 and the conductor 16.

As the solenoid core 35 is connected through its stem 34 to the dash-pot 37, any imperceptible lapse of time between the opening of the switch at 13 and 14 and the closure at 32 and 33 will be accounted for and the core 35 will be held against the action of the spring 40, so that the lever 38 of the normally closed valve 39 will not be operated until the circuit including the battery 17 is opened for a greater lapse of time than between the opening and closing of the above mentioned switches.

In order to keep a record of the number of times that the valve 39 is operated, a 65 register 41 is disposed in co-operative rela-

tion to the lever 38, the same only being operated when the spring 40 pulls the lever 38 to its full valve opening position.

Assuming that a train T' is within the block C as illustrated in dotted lines in Fig. 1, and that the train T is so disposed that the short rail sections 3—3' are engaged and consequently the above set forth circuit has been closed, it will be seen that the conductor 8 and its resistance 9 is cut out of the circuit, and that therefore the axle of the train T' being of less resistance, the circuit above referred to will include the axle of the train T' between the rails 1 and 2 of the block C, and the full force of the battery 21 will be thrown into the electromagnet 26, but not with sufficient force to operate the electromagnet 24. This energization of the electromagnet 26, will cause the attraction thereto of the armature 42, which is operably connected to the lever 44 of the valve 45, the same operating the valve 45 against the action of the spring 43 to open the valve and at the same time actuate the register 46 to record such operation. As the valve 45 is connected in the pipe 49, which in turn is a branch of the pipe 48 led from the pipe 47 of the auxiliary reservoir 46, of the air brake system, it is apparent that the air therefrom will then be directed through the pipe 49 into the cylinder 50. This cylinder 50 is mounted adjacent to the boiler of the locomotive and has mounted therein, the piston 51, whose stem 52 is disposed in co-operable relation with the short lever 53 pivoted at 54 to the free end of the throttle lever 55. This throttle lever 55 is mounted in the usual manner at 56, and controls the valve actuating or throttle rod 61.

Connected to the lever 53, which is in the nature of a bell crank lever, is a rod 57, which leads forward and is connected to the short lever 58, which in turn is operably connected to the pawl 59, so that upon the actuation of the bell crank lever 53, the pawl 59 is operated to disengage the segment 60, and thus permit the movement of the throttle lever 55 to control the throttle and to gradually reduce the speed of the train, under caution conditions. Should the train T however, continue and enter the block B, and finally come in contact with the rail sections 6 and 11, the resistance 5 being cut out, and the train T' being within the block C, the before mentioned circuit having the resistances 5 and 9 removed therefrom, will throw the full battery force into the electromagnet 24, which is then energized to move the armature 62 against the action of the spring 63, to in turn operate the lever 64 of the valve 65, the register or recorder 66 being operated simultaneously to indicate the number of times the valve 65 is operated. This action is an emergency or danger condition, and will immediately conduct 130

the air from the pipe 67 which is a branch of the pipe 47, into the pipe 68, and into the cylinder 69. In the cylinder 69 is mounted the piston 70, whose rod 71 is operably connected to the lever 72 carried by the throttle lever 55, and which in turn is operably connected through the link or rod 73 to the pawl actuating lever 58. Thus the pawl 59 is released from the segment 60 and at the same time, the lever 55 is pushed forward by the stem or piston rod 71 actuating the throttle to cut off the steam supply to the locomotive. As there is led from the cylinder 69 a pipe 74, air is conducted therefrom into the cylinder 75, which has mounted therein the piston 76 whose stem 77 carries the rack bar 78 which in turn is operably connected to the pinion 79 of the engineer's brake valve 80. Thus the brake valve 80 is operated to actuate the air brake system at the time that the steam is cut off, and the train is brought to a halt.

In order that the engineer's valve may not be too easily operated and bring the train to a stop too suddenly, there is interposed in the pipe 74 a valve 81, whose lever 82 is operably connected to the stem 83 connected to the stem 77. Thus as the piston 76 is operated by the air pressure, the valve 80 is gradually shut off producing more in the nature of an application effect in the engineer's brake valve and gradually applying the air brakes, as would be the case if the engineer were operating the same.

In order to provide a means for bringing the train to a halt should the switch members 13 and 14 not operate, and also should the circuit controlling the electromagnet 28 be broken or inoperative when the shoes S engage the rail sections along the right of way, the valve 39 is connected in the pipe 84 which is branched from the pipe 48 into the branch pipe 68. Thus the deenergization of the solenoid 19 and the consequent opening of the valve 38 due to its spring 40, will conduct the air into pipe 68 to operate the pistons 70 and 76 and thus produce the same effect upon the throttle 55 and the engineer's brake valve 80, as was produced when the solenoid 24 was fully energized.

In the detail form of shoe carried switch as illustrated in Figs. 2 and 3, the bolt 107 with the spring 108 form a resilient connection for the shoe S with the frame plate 106, a rod 109 being disposed through the plate 106 for sliding movement and operably connected to the shoe S so that motion is transmitted therethrough to the lever 110 which is operated in opposition to the spring 111 to thus open the circuit at the switch contacts 13 and 14. The lever 110 is journaled in the bracket 112 which may be suitably supported at any point of the present apparatus. As illustrated in Fig. 2, the switch 13 and 14 is shown in its normally closed

position, while in Fig. 3 it is shown in the open position or when the shoe S engages one of the ramp rails, as 3.

In the construction of shoe carried switch shown in Figs. 4 and 5, the plates 113 are attached to and depend from the plate 106', and are slotted to receive the pins 114 so as to assist in guiding the shoe S in its proper vertical position, the bolts 107' and the springs 108' being similar to the bolts 107 and the springs 108 heretofore referred to. The plate 106' is supported by a bolt 118 from the supporting plate 117, while the fixed contact 14 is carried by and insulated from the plate 117. Carried by the plate 106' and insulated therefrom is a pivoting support 117 for the lever 116, which in turn is operably connected at one end to the movable switch point 113 and at the opposite end to the projection 115 is connected to and insulated from the shoe S. Thus the parts may readily assume the position shown in Fig. 4, Fig. 4 illustrating the same in normal condition, while in Fig. 5 the switch is open as the shoe is in contact with the rail 3.

In the construction of shoe controlled switch shown in Fig. 6, the frame 106" is carried by the bolt 119 for sliding movement to and from the plate 120 which is a supporting plate. In this construction, it is desirable that means be provided for elevating the shoe S at a desired distance above the rail, so that the rails as 3 at certain points will not be engaged. In order to accomplish this, the cylinders 121 are suitably supported from above and are connected to the plate 120, the stem 123 of the piston 122 mounted therein, being operably connected to the plate 106", so that air admitted through the pipes 124 and 125 will elevate the pistons 105 and consequently the shoe S.

In order to provide a means to permit the engine to enter a prohibited zone, the construction as illustrated in Fig. 7 is employed. In this instance, the armature 62' of the electromagnet 24 is normally held in the position as shown by the spring 63', so that the catch 85 will engage and elevate the lever 86, which is normally moved to the dotted line position by the spring 87. This lever 86 is operably connected to the lever 64 of the valve 65, so that when the electromagnet 24 is energized, the lever 86 will be released and the valve 65 will be opened to operate the pistons 70 and 76. The handle 88 is connected to the lever 86, so that the engineman may grasp the same and hold the lever 86 elevated so that should the electromagnet 24 become deenergized, it is apparent that the valve 65 will remain inoperative, thus permitting the engineman to enter the prohibited zone.

Although no audible or visual signal means has been shown in the present apparatus as connected to the train carried con-

struction, it is apparent that whistles, bells, and other signaling means as lamps or indicators may be provided, to indicate to the engineman the condition arising, such as 5 caution or danger or the breakage of any of the circuits which would cause an emergency or danger operation of the device.

It is also apparent with the present apparatus, that traffic in both directions may be 10 controlled, on a single track railway or that the same may be applied only to traffic in one direction.

As illustrated in Fig. 8, the present apparatus including the rail sections 3^a and 3^b 15 are shown in operative connection with a block signaling electrical system, which includes the battery 89, the conductor 91, the rail 92, the conductor 93, the semaphore controlling system electromagnet 95, the conductor 96, the rail 97, and the conductor 90. There are disposed for operation with the 20 electromagnet 95, the two armatures 97 and 98, the armature 97 being the usual armature for controlling the semaphore mechanism (not shown), while the armature 98 25 controls the circuit to connect or disconnect the resistance 102 from the line, such resistance being similar to the resistance 9 heretofore described. Thus under normal conditions 30 with no train upon the rails 92 and 97, the electromagnet 95 will be energized, attracting the armature 98 so that the following apparatus will be connected to the rail sections 3^a and 3^b—the conductor 99, 35 the armature 98, the contact 100, the conductor 101, the resistance 102, the conductor 103 and the rail section 3^b. The contact 100 and the conductor 99 are both permanently 40 connected to the armature 98.

When a train is upon the rails 92 and 97, 45 and the battery 89 is short circuited, the electromagnet 95 becomes deenergized, releasing the armatures 98 and 97 under the influence of the spring 94, so that the resistance 102 is cut out from the connection 50 with the rails 3^a and 3^b, and the same condition would arise as heretofore recited in connection with the train T' in block C. Thus instead of the resistance being 55 connected to the rail sections 3^a and 3^b, the armature 98 will engage the contact 104, and cut out the resistance 102 by connecting the conductor 105 to the conductor 103 beyond the resistance 102.

Thus with this construction, the semaphore circuit is not interferred with, yet a train within the block will produce the danger condition to operate the piston 51 or pistons 70 and 76 as heretofore set forth.

What is claimed is:—

1. In a train control system, the combination with a partial track circuit including a pair of insulated traffic rails, a resistance between the rails, and a sub-rail connected to one traffic rail; of a normally closed train

carried circuit including a normally closed switch and a normally energized device for holding a train stopping means in inoperative position; and a partial train carried circuit coöperable with the partial track circuit 70 and including a contact member at one end coöperable with the sub-rail, an electrically operated device included in the partial train carried circuit for closing the circuit through the normally energized device when the normally closed switch is opened, and an electrically operated device for actuating a train stopping means and arranged to be operated only when the said resistance is cut out from the partial track circuit; the normally closed switch being operatively connected to the contact member whereby when the contact member engages the sub-rail, the normally closed switch will be opened; and means for electrically connecting the other end of the 80 partial train carried circuit and the other traffic rail.

2. In a train control system, the combination with a partial track circuit including a pair of insulated traffic rails, a resistance 90 between the traffic rails, and a pair of sub-rails connected to the respective traffic rails; of a normally closed train carried circuit including a pair of normally closed switches and a normally energized device for holding a train stopping means in inoperative position; and a partial train carried circuit coöperable with the partial track circuit and including a pair of contact members coöperable with the respective sub-rails, an electrically operated device included in the partial train carried circuit and operable to close the circuit through the normally energized device when the normally closed switches are opened, and an electrically operated device for actuating a train stopping means and arranged to be operated only when the said resistance is cut out from the partial track circuit; the normally closed switches being operatively connected to the contact members in order that the normally closed switches will be opened when the contact members engage the sub-rails.

3. In a train control system, the combination with a partial track circuit including a pair of insulated traffic rails, a resistance between the traffic rails, two sub-rails one of which is connected to one traffic rail, and a resistance between the sub-rails; of a normally closed train carried circuit including a normally closed switch and a normally energized device for holding a train stopping means in inoperative position; and a partial train carried circuit coöperable with the partial track circuit and including a contact member at one end coöperable with the sub-rails, an electrically operated device included in the partial train carried circuit and operable to establish the circuit through the said normally energized device when the 115 120 125 130

- normally closed switch is opened, a second electrically operated device for operating a caution train stopping means when the first mentioned resistance is cut out from the partial track circuit, and a third electrically operated device for operating an emergency train stopping means when both resistances are cut out; the normally closed switch being operatively connected to the contact member so that the normally closed switch is opened when the contact member engages the sub-rails; and means for electrically connecting the other end of the partial train carried circuit and the other traffic rail.
- 15 4. In a train control system, the combination with a partial track circuit including a pair of insulated traffic rails, a resistance between the traffic rails, two pairs of sub-rails, the sub-rails of one pair being connected to the respective traffic rails, a resistance between one of the said sub-rails and one of the sub-rails of the other pair, and a connection between the other sub-rails of the two pairs; of a normally closed train carried circuit including a pair of normally closed switches and a normally energized device for holding a train stopping means in inop-
- erative position; and a partial train carried circuit coöperable with the partial track circuit and including a pair of contact members coöperable with the sub-rails, an electrically operated device included in the partial train carried circuit and adapted to establish a circuit through the normally energized device when the normally closed switches are opened, a second electrically operated device for operating a caution train stopping means when the first mentioned resistance is cut out of the partial track circuit, and a third electrically operated device for operating an emergency train stopping means when both resistances are cut out; the normally closed switches being operatively connected to the contact members, whereby the said switches will be opened when the contact members engage the sub-rails.
- 20 25
- In testimony that I claim the foregoing as my own, I have hereto affixed my signature in the presence of two witnesses.
- ANTONIO CASALE.
